ATTORNEY.

UNITED STATES PATENT OFFICE.

ARTHUR B. REID, OF CHICAGO, ILLINOIS.

ATTACHABLE COPY-HOLDER.

SPECIFICATION forming part of Letters Patent No. 379,246, dated March 13, 1888.

Application filed July 16, 1887. Serial No. 244,564. (No model.)

To all whom it may concern:

Be it known that I, ARTHUR B. REID, of Chicago, in the county of Cook and State of Illinois, have invented a new and useful Improvement in Attachable Copy-Holders for Type-Writing Machines, of which the following, in connection with the accompanying sheet of drawings, is a full, accurate, and complete specification.

10 My invention relates to that class of devices used to hold or support the stenographer's note-book or other reference-copy at desirable position for observation by a type-writer operator.

15 My invention consists of three separate spring-fingers, the middle one of which clasps the book at the point of intersection of the pages, and the right and left fingers each hold, respectively, the pages turned to the right and left. As each finger works individually, the grasp is equal on each side of the book, notwithstanding that a greater number of pages and consequently a greater thickness may appear upon one side than upon the other.

20 25 My invention has a shank extending downward from the before-mentioned fingers, its lower end being attached by an adjustable fastening to a convenient place either at the back or upon the roller-carriage of the type-writing machine. The length of this shank will of course differ according to whether it is desired to attach to the lower back castings at or near the base of machine or to the roller-carriage, and must also differ somewhat in

30 35 length in accordance with the construction of the various makes of type-writing machines to which my invention may be applied. Its length may generally be stated as sufficient to reach from the point of attachment upward 40 to a proper and desirable place to hold the book or copy within the convenient range of vision of the operator when seated in the usual position to operate the machine. The shape of the said shank may be straight when the 45 point of attachment is not too far back from the operator; but where this is the case the shank may be formed to curve forward, thus bringing the copy nearer the operator, as it is necessary that this shank, with the fingers 50 above or at its upper end, should project some-

what above the top of the machine in order to hold the book or copy in a desirable position for consultation by the operator, and whereas this would be a disadvantage when the machine would not be in use, as preventing the 55 cover of the machine from coming down to its usual and proper position. To overcome this disadvantage I construct the said shank in either of the following ways: first, by placing a spring-joint at such position in its length as 60 will allow the upper portion to be turned backward and downward out of the cover's way, or, second, by constructing the shank in two portions, one of which shall be tubular in form and in size to fit over the second section or part, so that it may be drawn upward after the manner of extending the draws of a telescope. 65

In further describing my invention reference may be had to the accompanying sheet of drawings, of which—

70 Figure 1 is a face plan of the clamp or portion of my invention directly used to engage and hold the copy. Fig. 2 is a side elevation of that portion of my invention shown in plan 75 in Fig. 1. Figs. 3 and 4 are respectively face and side views of the shank as constructed with the spring-joint therein. Fig. 5 is a perspective of the device whereby I attach my invention to a type-writing machine. Fig. 6 shows my invention attached to a type writing machine, the shank being bent in such form as to bring the part engaging the copy over the machine and quite near to the operator. Fig. 7 shows my invention attached to a type- 80 writing machine different in structure from that shown in Fig. 6, my purpose of bringing the copy conveniently within the range of the operator's vision being then accomplished by the employment of a straight shank. Fig. 8 85 shows a section of a shank constructed upon the second or telescopic plan above set forth. 90

I also in the construction of my invention use a single bar for the shank, without joint or separable parts, thus cheapening the construction for those who prefer to remove the copy-holder from the machine when placing the cover upon it. 95

In the several figures like letters of reference indicate like parts. 100

A is the clamp intended to engage and hold the copy, the minor parts of which are indicated as follows:

5 a, b, and c are three spring-fingers so constructed (when at rest upon the plate j) that their extremities may curve outward sufficiently to admit a copy-book to enter at their extremities and be pressed downward between them and frame j without, in ordinary cases, 10 the necessity of using other means to raise them.

15 d, e, and f are three springs exerting their influence, respectively, upon the several fingers a, b, and c, causing said fingers to grip and hold the copy between themselves and the lyre-shaped frame j.

20 g, h, and i are rear extensions of the fingers a, b, and c, and are so arranged as to form thumb-pieces, whereby, by a downward pressure thereon, the fingers a, b, and c may be raised, these three thumb-pieces being arranged side by side and constructed of such size that, if desired, they may be collectively covered at one time by one thumb and the 25 three fingers simultaneously raised.

25 j is a lyre-shaped (preferably) frame, upon which fingers a, b, and c press when not in use, and between which and said fingers a, b, and c the copy is held by the downward pressure of said fingers received from the several springs, d, e, and f.

30 k is a rod or pin passing through a number of upwardly-extending studs from frame j, and also passing through the fingers a, b, and c, forming an axis or fulcrum upon which they move, and also upon which the spiral springs 35 d, e, and f are coiled.

B is the upper end of shank.

C is the lower end of shank.

40 D is a rivet by which the parts B and C are fastened together when shank is constructed to fold or double backward, and forms the pivot of the joint in shank.

E and E' are points at which an indentation 45 in one portion of the shank receives a nipple upon the other portion, thus holding the shank firm when extended, the overlapping ends of parts B and C having sufficient spring to force the nipples into the corresponding indentations when brought to the proper position.

50 F is a type-writing machine (shown in Fig. 7) with my invention attached.

G is one form of the device which I use to attach my invention to a type-writing machine, 55 as shown in Fig. 6.

H is a longitudinal slot in part G, which may be wide, narrow, straight, curved, or irregular in form, and in the general position shown, or otherwise, so that it may be made 60 to fit upon any desired part of the frame-work of any type-writing machine to which my invention may be attached.

I is a well or cavity in part G, of such size

and shape as to receive the lower end of the shank supporting the clamp.

65

J is a set-screw in part G, which may be turned up to hold shank firmly in place in cavity I.

K is a set-screw, which may be used to hold part G firmly to such part of the machine to 70 which it may be attached.

L is a type-writing machine, to which my invention may be attached, as shown in Fig. 6.

M and N show, respectively, the two parts of the shank of my invention when 75 constructed upon the telescopic plan above specified.

I reserve to myself a considerable latitude in the shape and formation of part G, in order that the formation of the opening H may be 80 such as to stride the differently-shaped parts of frame-work of the various type-writing machines now in use, or which may come in use, and reserve the right to place the opening H either at the top, as shown, or at the bottom 85 or side.

The operation of my invention is accomplished by attaching part G to a type-writing machine, and then fastening the above-mentioned shank in cavity I, thus bringing clamp 90 A to a proper position. The copy-book may then be inserted under the extremity of the fingers a, b, and c, and by pressing downward the fingers will raise and receive the book between themselves and the frame j. In inserting single sheets of paper or other matter not sufficiently substantial to press the fingers outward, the fingers may be raised by pressing downward upon the thumb-pieces g, h, and i 95 sufficiently for its reception.

100

I am aware that certain devices for holding music have been in use wherein fingers press down upon a lyre-shaped frame. I therefore do not broadly claim this; but

I do claim—

1. A clamp consisting of fingers formed with an outward curve at their several extremities, so as to admit of a copy-book being pressed downward under them, in combination with springs, thumb-pieces, and a frame, 110 as specified.

2. In a copy-holder for type-writing machines, the combination of part G, as specified, with a jointed or tubular shank.

3. The combination of clamp A, as specified, with a jointed shank, as specified.

4. The combination of clamp A, as specified, with a tubular or telescopic shank, as specified.

In witness whereof I have hereunto set my 120 hand, this 9th day of July, A. D. 1887, in the presence of two subscribing witnesses.

ARTHUR B. REID.
